UNITED STATES PATENT OFFICE

171,717

SPIKED SHOE

George H. Langford, Glendale, Calif.

Application April 24, 1953, Serial No. 24,672

Term of patent 7 years

(Cl. D7—7)

To all whom it may concern:

Be it known that I, George H. Langford, a citizen of the United States, residing at Glendale, in the county of Los Angeles, State of California, have invented a new, original, and ornamental Design for a Spiked Shoe, of which the following is a specification, reference being had to the accompanying drawings, forming a part hereof.

Figures 4 and 5 are front and rear elevational views, respectively, of the shoe as shown in Figure 2.

The dominant feature of the design resides in the portions shown in full lines.

I claim:

The ornamental design for a spiked shoe, substantially as shown and described.

GEORGE H. LANGFORD.
